UNITED STATES PATENT OFFICE.

JOSEPH N. MAHONEY, OF WILKINSBURG, AND WALTER M. AUSTIN, OF SWISSVALE, PENNSYLVANIA, ASSIGNORS TO WESTINGHOUSE ELECTRIC AND MANUFACTURING COMPANY, A CORPORATION OF PENNSYLVANIA.

CIRCUIT-INTERRUPTER.

1,278,967.

Specification of Letters Patent. Patented Sept. 17, 1918.

Application filed August 7, 1914. Serial No. 855,649.

To all whom it may concern:

Be it known that we, JOSEPH N. MAHONEY, a citizen of the United States, and a resident of Wilkinsburg, in the county of Allegheny and State of Pennsylvania, and WALTER M. AUSTIN, a citizen of the United States, and a resident of Swissvale, in the county of Allegheny and State of Pennsylvania, have invented a new and useful Improvement in 10 Circuit-Interrupters, of which the following is a specification.

Our invention relates to circuit interrupters and particularly to those that are automatically operated.

One object of our invention is to provide 15 means for decreasing the current in the winding of a closing, holding and tripping electromagnet of a circuit interrupter after the contact members of the same are engaged.

Another object of our invention is to provide 20 a simple type of toggle and tripping mechanism for a circuit interrupter having means for removing part of the load from the operating electromagnet when the circuit interrupter is in its closed position.

It has heretofore been proposed to provide 25 a single electromagnet winding for closing a circuit interrupter, for holding the same in a closed position and for tripping the same. Since it does not require so large a current to retain a circuit interrupter of this type in its closed position as it does to close the same it is highly advisable that 30 some simple means be provided for reducing the current in the electromagnet winding when the circuit interrupter is closed.

According to the present invention we 35 provide a circuit interrupter comprising an operating toggle mechanism having a lost motion connection, an operating, holding and tripping electromagnet and a resilient member for opposing the action of the same, and we so arrange the toggle mechanism, the 40 electromagnet and the resilient member that the load upon the electromagnet is reduced when the contact members are engaged, and we also provide means for decreasing the current traversing the winding of the 45 electromagnet in accordance with the reduction in the load upon the same.

Our device is so arranged that the load upon the electromagnet, after the contact members are engaged, is only sufficient to

overcome the pressure of the resilient member. Thus, when the current traversing the electromagnet is interrupted, the resilient member will trip the circuit interrupter, substantially as hereinafter set forth.

Figure 1 of the accompanying drawing is 55 a side view, partially in elevation and partially in section of a circuit interrupter embodying our invention; Fig. 2 is a fragmentary front elevational view of the circuit interrupter shown in Fig. 1, and Fig. 3 is a 60 diagrammatic view of circuit connections of one application to which our invention may be applied.

The circuit interrupter embodying the present invention is especially adapted to 65 be employed in systems in which it is desired to connect together two conductors 1 and 2 (Fig. 3) when the voltage between each of the said conductors and a common return conductor 3 is substantially the same, 70 the circuit interrupter being shown conventionally at 4. However, our invention may be employed equally well in any place where an electrically operated circuit interrupter 75 is needed.

The electromagnet winding 5 of the circuit interrupter 4 is connected in series with a resistor 6 to form a circuit from the conductor 1 to the return wire 3, substantially 80 as shown. A relay 7 is provided having two supplemental windings 8 and 9, a movable core member 10, and a bridging contact member 11, substantially as shown. One of the windings of the relay 7 is connected between the conductors 2 and 3 and the other 85 is connected between the conductors 1 and 3. These windings are so proportioned that the movable core member 10 of the relay 7 will be drawn upwardly when the voltages across the circuits are of predetermined values. 90 The bridging contact member 11 and its co-operating stationary contact member 11^a form a switch for the circuit that includes the electromagnet winding 5 and the resistor 6. A knife blade 13 which co-operates 95 with a stationary contact member 14 is adapted to short circuit the resistor 6 when the circuit interrupter 4 is opened.

The circuit interrupter 4 comprises main stationary contact members 15, a main 100 bridging contact member 16, a stationary auxiliary contact member 17, a movable auxiliary contact member 18, a stationary

tertiary contact member 19, a movable tertiary contact member 20 and a toggle mechanism 21. The contact members 16 and 20 are attached to an arm 23 that is pivotally mounted upon a pin or shaft 22 supported between two brackets 22^a. The brackets 22^a are attached to a base member 22^b. Upon a pin or shaft 24, also supported between the two brackets 22^a, is pivotally mounted an arm 25 to which the contact member 18 is attached. The pivotally mounted arms 23 and 25 are operatively connected together by resilient members 16 to provide a time interval between the operation of the same. 10 The contact members and means for supporting the same are substantially the same as is shown in a copending United States application Serial No. 535,437, filed Dec. 29, 1909, and assigned to the Westinghouse Electric & Manufacturing Company.

To the base member 22^b is attached an operating electromagnet 27 which comprises, besides a winding 5 and a movable core member 12, a stationary core member 28, a spring 29 and adjustable limiting screws 30. The springs 29 are disposed within the movable and stationary core members of the electromagnet 27 and are arranged to oppose the operation of the electromagnet 27, as hereinafter set forth.

The toggle mechanism 21 comprises a bell crank lever 31 that is pivotally mounted upon a shaft 31^a supported by the brackets 22^a, links 32 that operatively connect the pivotally mounted arm 23 to the upper arm of the bell crank lever 31, and a link 33 that operatively connects the other arm of the bell crank lever to the movable core member 12 of the electromagnet 27. The link 33 is provided with a relatively large opening 34 where it connects with the bell crank lever 31 to form a lost motion connection between the movable core member 12 of the electromagnet 27 and the bell crank lever 31. The springs 29 are disposed about rods 35 which are located within openings in a portion 28^a of the stationary core member of the electromagnet 27. The rods 35 engage the knife blade members 13 to effect 50 disengagement of the same from the stationary contact member 14 when the springs 29 are compressed. The limiting screws 30 are adjusted to support the weight of the movable parts of the interrupter when the same is closed and thus restrain the same in its closed position. The portion 28^a of the stationary core member 28 is screw threaded and adapted to be adjustable with respect to the main portion of the stationary core member.

When the voltage between the conductors 1 and 3 and 2 and 3, respectively, are substantially the same and of such value as to energize the relay 7 sufficiently to draw the 60 movable contact member upwardly, current

will traverse the winding 5 of the circuit interrupter 4 causing the movable core member 12 to move downwardly. The downward movement of the movable core member 12 rotates the bell crank lever 31 in a counterclockwise direction forcing the movable arms 23 and 25 in a counter-clockwise direction to cause the engagement of the respective stationary contact members of the circuit interrupter. The downward movement 70 of the movable core member 12 compresses the spring 29 to cause disengagement of the knife blade member 13 from the stationary contact member 14. Thus, the short circuit around the resistance 6 is opened to decrease the current traversing the winding 5. The toggle mechanism 21 is restrained from opening the circuit interrupter by reason of its being overset to assume an "off center position" that is determined by 80 the adjustable limiting screws 30.

If the voltage between either of the conductors 1 and 2 and the common return conductor 3 decreases, the movable core member 10 of the relay 7 will move downwardly to interrupt the current traversing the winding 5 of the electromagnet 27. Since the current that normally traverses the winding 5 is only sufficient to overcome the springs 29, when the flow of current therein 90 is interrupted, the springs will expand, causing the movable member 12 to move upwardly throwing the toggle mechanism 21 across its dead center position to interrupt the circuit between the conductors 1 and 2. 100 The opening 34 in the link 33 permits the movable core member to attain a relatively great amount of energy before the toggles are upset or collapsed. The upward movement of the movable core member 12 and the rods 35 permits the spring 36 to move the knife blade member 13 into engagement with the stationary contact member 14. In this position, the circuit interrupter is again ready for operating when the relay 7 is 110 again sufficiently energized.

While we have shown our invention in its preferred form, it is not so limited, but, is capable of various modifications within the scope of the appended claims.

We claim as our invention:

1. A circuit interrupter comprising stationary contact members, movable contact members, a pivotally mounted arm for the movable contact members, a bell-crank lever, a link for operatively connecting the pivotally mounted arm to one arm of the bell-crank lever, an electromagnet mounted entirely below the bell-crank lever, and a pin-and-slot lost-motion connection between 120 the other arm of the bell-crank lever and the movable member of the electromagnet.

2. A circuit interrupter comprising stationary contact members, movable contact members, a pivotally mounted arm for the 130

- movable contact members, a bell-crank lever, a link for operatively connecting the pivotally mounted arm to one arm of the bell-crank lever, an electromagnet mounted 5 entirely below the bell-crank lever, and a link having a lost-motion connection between the other arm of the bell-crank lever and the movable member of the electromagnet.
- 10 3. A circuit interrupter comprising co-operating movable and stationary contact members, a bell-crank lever, a link for operatively connecting the movable contact member to one arm of the bell-crank lever, an 15 operating electromagnet disposed entirely below the bell-crank lever, and a link having a lost-motion connection between the movable member of the electromagnet and the other arm of the bell-crank lever.
- 20 4. A circuit interrupter comprising co-operating movable and stationary contact members, a bell-crank lever, a link for operatively connecting the movable contact member to one arm of the bell-crank lever, an 25 operating electromagnet disposed entirely below the bell-crank lever, a link having a lost-motion connection between the movable member of the electromagnet and the other arm of the bell-crank lever, and a spring 30 for opposing the closing movement of the electromagnet.
5. A circuit interrupter comprising a stationary contact member, a movable contact
- member, a pivotally mounted arm for the movable contact member, a bell-crank lever mounted below the pivotally mounted arm, a link for operatively connecting the pivotally mounted arm to one arm of the bell-crank lever, an operating electromagnet mounted entirely below the bell-crank 40 lever, and a link operatively connected to the movable member of the electromagnet and having a lost-motion pin-and-slot connection with the other arm of the bell-crank lever.
6. A circuit interrupter comprising a stationary contact member, a movable contact member, a pivotally mounted arm for the movable contact member, a bell-crank lever mounted below the pivotally mounted arm, 45 a link for operatively connecting the pivotally mounted arm to one arm of the bell-crank lever, an operating electromagnet disposed below the bell-crank lever, and a link operatively connected to the movable member of the electromagnet and having a lost-motion pin-and-slot connection with the other arm of the bell-crank lever.

In testimony whereof, we have hereunto subscribed our names this 30th day of July, 1914.
